UNITED STATES PATENT OFFICE.

JOSEPH S. LACH, OF STAMFORD, CONNECTICUT, ASSIGNOR TO THE YALE & TOWNE MANUFACTURING COMPANY, OF STAMFORD, CONNECTICUT.

SECURING OR CLAMPING MEANS FOR LOCK CYLINDERS.

Application filed November 14, 1925. Serial No. 69,034.

This invention relates to improvements in securing or clamping means for lock cylinders used with mortise locks,—one object of the invention being to provide simple and efficient clamping means which shall be so constructed that the same will automatically adapt itself to irregularities of two cylinders, as when the groove or scoring for the securing device is deeper in one cylinder than in the other.

With this and other objects in view, the invention consists in certain novel features of construction and combinations of parts as hereinafter set forth and pointed out in the claim.

In the accompanying drawings,—

Figure 1 is a view partly broken away and partly in section showing an embodiment of my invention.

Figure 2 is a sectional view taken at right angles to Figure 1 and including a portion of a door, and

Figure 3 is a separate view of the cylinder securing or clamping device.

A portion of a door is represented at 1 and provided with a mortise to receive a lock casing 2. The door and also the lock casing are provided with openings for the accommodation of two cylinder locks represented at 3—4. The cooperation of the plug members with the bolt mechanism within the casing 2 may be of any approved construction and need not, so far as my present improvements are concerned, be further described.

The lock cylinders 3 and 4 are provided with grooves or scoring 5 for the reception of securing or clamping means to prevent the cylinders from turning. It sometimes happens that the grooves or scoring in one cylinder may be deeper than the grooves or scoring in the other cylinder, or the grooves or scoring in the same cylinder may vary in depth and the securing devices heretofore employed will not properly adapt themselves to such irregularities.

My improved securing or clamping means comprises a yoke or carrier 6, between the free ends of the parallel members of which, a dog 7 is pivotally supported intermediate

of its ends and provided with fingers 8—8 to engage in grooves 5 of the respective cylinders 3 and 4. A threaded shaft 9 is swiveled as at 10 within the locking casing 2 and is provided at one end with a threaded shank 11 which passes through a hole in one end of a yoke or carrier 6 and has threaded engagement with the wall of said hole. The other end of the shaft 9 is provided with a slot 12 for the accommodation of a screwdriver, access for the latter to the slotted end of the shaft 9 being afforded by an opening 13 in a plate 14 countersunk in the edge portion of the door,—said plate 14 being (if so desired) a part of the lock casing 2.

By turning the shaft 9 in one direction, the yoke or carrier will be moved forwardly to engage the fingers of the dog 7 in the grooves 5 of the respective cylinders and as said dog is pivotally connected with the carrier, it will automatically adapt itself to the depths of the grooves in the respective cylinders, even though the groove in one cylinder may be deeper than the groove in the other cylinder, as illustrated in Figure 2. The dog 7 may also be provided with fingers 15—15 projecting in the opposite direction to that of the fingers 8 and located closer together than the latter. In case the clamp is used with one cylinder only, one of the fingers 15 will rest against the inside face of the case, thus holding the clamp against the cylinder. It will be observed that the yoke is free of all external flanges, enlargements or other projections and it may, therefore, be very cheaply made without any loss of efficiency and may be mounted in a narrower case than was permissible with previous devices. The case is provided with longitudinal slots to accommodate the pivotal movement of the dog as the latter adjusts itself to the differences between the grooves or recesses in the two cylinders, and the fingers 15, besides engaging the case to limit the pivotal movement of the dog, engage between the top and bottom of the yoke in such manner as to prevent rocking of the dog along its pivot, without requiring great width in the yoke for the support of the dog.

Having fully described my invention what I claim as new and desire to secure by Letters-Patent, is:

Means for securing lock cylinders comprising a yoke having open sides, a dog pivoted in the inner end of the yoke and constructed at its inner end to engage the lock cylinders, fingers projecting from the outer end of the

dog between the top and bottom of the yoke and arranged to extend through the open 10 sides of the yoke as the dog moves pivotally, and means for securing and adjusting the yoke.

In testimony whereof, I have signed this specification.

JOSEPH S. LACH.
